BELT LOOP SEWING MACHINE

Joseph Galkin, New York, N. Y.

Application June 14, 1940, Serial No. 340,577

3 Claims.

(Cl. 112—2)

This invention relates to improvements in sewing machines whereby belt loops for trousers are automatically produced in a single operation by mechanism which cuts scraps of cloth into strips and folds said strips into belt loop form and feeds said folded material with upper and lower feed-dogs while being stitched with two spaced needles.

An object of this invention is to provide two upper 4-motion feed-dogs resiliently mounted one behind the other for joint up and down movement, so as to automatically adapt itself for feeding materials of different thicknesses.

Another object of this invention is to provide a combined feeding means and reciprocatory cutting means comprising two reciprocatory cutters respectively mounted at each side of said feeding means and adapted to simultaneously cut a scrap of material to predetermined strip form and feed said strip towards the stitching mechanism.

Another object of this invention is to provide a folder disposed between the trimming and stitching mechanism for folding both trimmed edges of the strip and having a through linear passage with parallel walls in its upper face for a rectangular feed-dog adapted for automatically feeding the folded material through the folder and along a portion of the length of the presser-foot and directly to the stitch forming mechanism.

This application is a continuation in part of my application, Serial No. 298,504, filed October 7, 1939.

Another object of this invention is to provide in a belt loop machine of the character described a presser-foot having a passageway centrally and lengthwise thereof, the width of said passageway being adapted for receiving finished belt loops, and a feed-dog constructed with feeding teeth in its central portion only and the said teeth being positioned for movement inside said passageway for feeding finished belt loops.

Another object of this invention is to provide means for feeding a tape into the folded belt loop material, the tape serving for chaining the threads and so that the threads will not break even after the belt loop fabric has passed the needles.

With the above and other objects in view, the invention will be hereinafter more particularly described, and the combination and arrangement of parts will be shown in the accompany-

ing drawings and pointed out in the claims which form part of this specification.

Reference will now be had to the drawings, wherein like numerals of reference designate corresponding parts throughout the several views, in which:

Figure 1 is a front elevation of a standard design two-needle sewing machine having my invention applied thereto.

Figure 2 is a fragmentary plan view of the belt loop sewing machine.

Figure 3 is an end view of the belt loop sewing machine, partly in section.

Figure 4 is a fragmentary plan view showing reciprocatory top feed mechanism for feeding the fabric.

Figure 5 is a fragmentary side view of the feeding mechanism shown in Figure 4, the presser-foot being omitted.

Figure 6 is a plan view of the needle-plate and folder and shear blades, on an enlarged scale.

Figure 7 is a side view of the presser-foot, needle-plate, folder and shear blades.

Figure 8 is a cross-sectional view, the section being taken as on line 8—8 in Figure 6, the foot being on the needle-plate.

Figure 9 is a cross-sectional view of an assembled top feed pressure bracket and plunger for resiliently downpressing the top feed dogs.

Figure 10 is a top plan view of the lower feed dog.

Figure 11 is a perspective view of two shear blades in assembled relation in a blade carrier.

Figure 12 is a diagrammatic sectional view on an enlarged scale through the folder.

Figure 13 is a fragmentary plan view showing a modified drive for the movable shear blades.

Figure 14 is a cross-sectional view of the shear blade drive shown in Figure 13, the section being taken as on line 14—14 in Figure 13.

In the illustrated embodiment of the invention, the numeral 10 indicates the work supporting base of a sewing machine embodying my invention and which comprises the usual standard 11, having an overhanging arm 12 with a head 13 at its free end. In the head 13 is journaled the usual reciprocatory needle-bar 14 carrying two spaced needles 15. The needle-bar is reciprocated by a lever 16 mounted on a pivot shaft 17. A looper 18 is oscillated and cooperates with the two spaced needles. The looper thread interlocks with the needle threads to form stitching as is well known in the sewing machine art.

The material worked upon is held down by a

presser-foot 19 resting on a needle-plate 20 secured to the work supporting base 10.

Projecting through the needle-plate 20 is a lower feed-dog 21. The feed-dog 21 is carried by a feed-bar 22 attached to a feed rocker 23. The feed rocker 23 is oscillated by an arm 24 connected in the usual manner to a link or pitman 25 on the forward end of the main shaft 26. The feed-bar 22 is raised and lowered by an eccentric 27 on the main shaft 26.

By actuating a screw 28, Figure 3, the link or pitman 25 is caused to move to or away from the center of the main shaft 26 and causes the arm 24 to impart a larger or smaller swing to a stub shaft 29 and feeding movements to the feed-dog 21.

The foot 19 has its shank 30 secured to the lower end of a presser bar 31 which is supported in the head 13 in the usual manner. Pressure is maintained upon the foot 19 by a leaf spring 32 pressing upon the presser-bar 31.

The invention is particularly directed to a combination of mechanisms operating upon scraps of cloth for forming belt loops therefrom in a single operation. The invention consists of a trimming mechanism 33 for trimming two fabric edges so as to prepare a strip of predetermined width, a folder 34 for folding the strip into belt loop form and directing the same to the stitching mechanism for stitching the belt loop. The invention also provides a top feed-dog 35 for feeding the strip to and through the trimming mechanism, and a top feed-dog 36 for feeding the cut strip to and through the folder and to the stitching machine. The top feed-dogs 35 and 36 are operated in timed relation with the lower feed-dog 21.

The forward top feed-dog 35 feeds the scrap fabric to and through movable shear blades 37, 37' held in carriers 38, 38'. The movable blade carriers are slidably mounted on a rock shaft 39. The carriers 38, 38' are keyed to the shaft 39 by a key 40 and are resiliently pressed by coil springs 41 in the direction of the stationary shear blades 47. The springs 41 react against collars 42 fixedly mounted on the shaft 39. The stationary shear blades 47 are held in properly spaced cutting relation by being held in a blade carrier 43 of the desired width. The movable shear blades 37, 37' thus cooperate with the stationary shear blades 47 to cut a fabric strip of predetermined width.

The movable shear blades 37, 37' are given substantially vertical movements by the carriers 38, 38'. The carriers slidably engage the elongated key 40. The key is held in fixed parallel relation with the rock shaft 39 by being held in an arm 44 fixed to said shaft. An arm 45 has been fixed to one end of the shaft 39 and is pivotally connected to a vibrating connection 46 operated by an eccentric 48 on the main shaft 26. As the shaft 26 rotates, the rock shaft 39 actuates the movable shear blades 37, 37' once for each revolution of the main shaft 26.

As shown in Figures 4 and 5, the rearward top feed-dog 36 is elongated and serves for feeding the folded strip of fabric through the folder 34 and to the central portion of the feed-dog 21. The feed-dog 36 has been mounted on a pivot 53 at one end of a top feed bracket 54 and adapted for reciprocating motion in a linear passage 55 extending through the entire length of the upper wall of the folder 34. The top feed bracket 54 has been mounted on a pivot 56 at the upper end of a feed-bar extension 57 which is raised

and lowered by an eccentric 58 mounted on the main shaft 26.

As shown in Figures 4 and 5 the top feed-dog 35 for feeding the scrap or strip fabric to the shear blades 37, 37' has been pivotally mounted on a pin 60 passing through the top feed-dog 36. The top feed-dog 35 is positioned for movement between the movable blades 37, 37'. A leaf spring 61 secured at one end by a screw 62 to the feed-dog 35 and in tensioned engagement at its free upper end with the upright front wall of the top feed-dog 36 serves to press the top feed-dog 35 against the upper surface of the blade carrier 43 for the stationary blades 47, and in pressure contact with the work. The upper surface of the blade carrier 43 is at the level of a raised front extension 63 of the base 10.

The top feed-dog 35 has feeding teeth 64 extending across the entire lower surface thereof. The teeth 64 face in the same direction as the teeth 65 on the top feed-dog 36, and in the same direction as the teeth 66 on the lower feed-dog 21.

As shown in Figure 4, it will be seen that the front top feed-dog 35 is considerably wider than the rear top feed-dog 36. In practice, the feed-dog 35 feeds strip fabric cut to the size of a blank belt loop, while the feed-dog 36 feeds folded fabric of the proper belt loop form.

The top feed bracket 54 is normally maintained in a substantially horizontal position by means of a collar 50 fixed to the pivot 56 and having a vertical extension 67 resting against a horizontally adjustable screw 68 in the feed-bar extension 57. The feed-bar extension 57 is carried by a feed-bar 69 attached to the feed rocker 23, and is caused to move up and down by the eccentric 58 on the main shaft 26.

I have provided a resilient means for down-pressing the top feed-dog 36 into engagement with the folded belt-loop fabric and so that the teeth of the top feed-dog will be adapted for feeding the belt loop fabric through the folder and directly to the needles. This resilient means comprises a tubular guide or housing 85 secured to the head 13 by a flange 86. As shown in Figure 9, a top feed plunger 87 has a collar 88 on which a coil spring 89 seats and reacts against an adjusting screw 90. The lower end of the plunger 87 is thus adapted to resiliently downpress the bracket 54 and both feed-dogs 35 and 36 as a unit. The contacting portion of the end 87 houses a ball 91.

It will thus be noted that the front top feed-dog 35 is resiliently downpressed by the spring 89 against the upper cutting surface of the blade 43 independently of the joint downpressing by the spring 89.

As shown in Figure 5, it will be noted that the length of the top feed-dog 36 is longer than the length of the passageway in the folder 34 and that the top feed-dog engages the folded strip in the folder and feeds it the entire length of the folder, along a portion of the length of the presser-foot, and directly to the needles.

When the sewing machine is in operation, the top feed bracket 54 is actuated up and down by the eccentric 58 and forward and backward by the feed rocker 23. The attached top feed-dog 36 and the pivotally mounted top feed-dog 35 thus have 4-motion feeding movements imparted thereto, similar to the 4-motion feeding movements of the feed-dog 21. The lower feed-dog feeds the folded fabric through the passageway

92 by pressure contact with the lower surface of said fabric.

As best shown in Figure 6, the feed-dog 21 is made with feeding teeth 66 in its central portion only. The overall width of the feeding teeth 66 is made to correspond to the width of the belt loops in folded and finished form. The centrally positioned teeth serve to feed the folded belt loop strip through the passageway 92 in the foot 19. It is to be noted that the side bars 93, 93 of the feed-dog 21 do not have any teeth and merely serve to connect the front and rear teeth 66, 66, in unitary relation.

As shown in Figure 7, the foot 19 comprises a center member 94 which is vertically movable in the passageway 92 and which is pressed downwardly by an elongated spring 95 into contact with the needle-plate 20 and holds the threads against the needle-plate to allow chaining of said threads. The rear end of member 94 is downpressed by a coil spring 102.

The center member 94 has a vertical aperture 96 through which passes a pivot 97. The member 94 has an upwardly sloping front end 98 and a bevelled rear end 99 to permit the said member to rise when the folded belt-loop passes under its front end.

It is to be understood that the foot 19 remains in direct contact with the needle plate 20 under normal operating conditions and that the side walls defining the passageway 92 in the foot jointly with the needle-plate surface and with the center member 94 form a rectangular channel corresponding to the rectangular cross-section of a finished belt-loop. The height of the side bars 93 of the feed-dog 21 is reduced so as to leave a clearance between the upper surface of said bars and the lower surface of the foot 19. The raising of the center member 94 is accomplished by the central teeth 66.

As shown in Figures 6 and 12, the folder 34 has a tongue 120 about which the cut belt loop strip is folded underneath the strip. The tongue is supported by a central support 121.

I have provided a knife shield for the fingers of the operator. The shield comprises two angular arms 116 which are integral with the folder 34 and extend forwardly above and between the movable blades 31, 31'. The reciprocable feed-dog 35 has clearance on each side thereof to operate freely between the said angular shield arms.

Referring to Figures 2 and 5, it will be noted that I have provided a slot 115 in the raised front extension 63 of the base 10. The slot 115 is positioned centrally of the folder 34 and serves for feeding a tape 117 through the folder and provides a positive means for feeding the finished belt loops 118 when passing beyond the needles 15, without breaking the thread. The tape is fed from a spool (not shown) below the base of the sewing machine. The tape 117 passes below the top feed-dog 35 and below the top feed-dog 36, through the folder 34, and to the needles and is stitched integrally within the belt loop 118. The tape is concealed inside the belt loop and is visible at both ends of the finished belt loop. The tape forms a continuous fabric strip extending from one belt loop to another, and when one scrap of fabric has been formed into a belt loop and passes the needles, the tape extends rearwardly from the finished belt loop and provides fabric on which the needles can continue their stitching operations. The tape thus serves as a means for chaining the threads without breaking them even after the finished belt loop

has passed the needles a considerable distance. The top feeding mechanism may be operated with or without the tape 117.

As best shown in Figures 1, 2, 3 and 8, the foot 19 has a lug 124 extending sideways therefrom. The lug 124 is positioned below the top feed bracket 54. It is thus possible to raise the bracket 54 by raising the bar 31.

As shown in Figure 11, the stationary shear blades 47 are made in the form of a centrally supported square, with four cutting edges. Each blade may thus be turned ninety degrees about a pivot screw 123 to bring an interchangeable cutting edge into the upper cutting position. The overall width of an assembled set of blades and blade carrier 43 may be varied to suit different widths of belt loops. The carrier 43 has been fastened to an elongated bracket 125 in which the shaft 39 is mounted.

Figures 13 and 14 show a modified drive for the movable shear blades. As shown, the blade carrier 138 has been rotatably mounted on a stationary shaft 139. The shaft 139 is fixed in the bracket 125. The blade carrier 138 has an integral extension 140 which is ball-jointed at its lower end at 141. The ball-joint 141 is connected to one end of a vibrating connection 142. The opposite end 143 of the connection 142 is connected to the eccentric 27. The eccentric 27 is thus adapted to actuate the shear blades 138, 138', and the feed-dog 21. A pin 144 fixed in the carrier 138 and slidably mounted in the carrier 138', serves to actuate the carrier 138' about the fixed front shaft 139.

In accordance with the patent statutes I have described and illustrated the preferred embodiments of my invention, but it will be understood that various changes and modifications can be made therein without departing from the spirit of the invention as defined by the appended claims.

I claim:

1. In combination with a sewing machine for forming stitched belt loops from untrimmed scrap fabric in a single operation, comprising mechanism for simultaneously trimming both edges of a strip of fabric and downfolding the trimmed edges while top feeding the unfolded and the folded portions of said strip with pivotally connected 4-motion top feed-dogs including teeth extending beyond the folder and along a portion of the length of the presser-foot, a work supporting base and two spaced needles, two top feed-dogs placed one behind the other and being mounted for 4-motion feeding movements in front of said needles, means for resiliently downpressing said top feed-dogs, reciprocatory shear blades mounted on a shaft positioned below said work supporting base, said blades being respectively positioned on opposite sides of the forward top feed-dog for cutting an automatically fed strip of fabric of predetermined width, a foot having two rigid side bars forming a fixed guideway centrally and lengthwise thereof, a folder for folding both side edges of said sheared strip of fabric underneath said strip and having a linear passage in its upper wall and a folding tongue positioned above said work supporting base, said reciprocatory shear blades coacting with a stationary duplex blade having a flat upper surface, said surface being positioned in alignment with said folder tongue, the rear top feed-dog being mounted in said passage for feeding the folder fabric through said folder and along a portion of the length of said foot and directly to said needles, the width

of said foot guideway being adapted for folded belt loops, a spring-pressed center presser-foot member vertically movable in said guideway and having needle holes, a lower feed-dog having feeding teeth only at its central portion and being positioned for movement inside said guideway for feeding folded belt loops pressed down by said center presser-foot member, said lower feed-dog teeth being positioned at the front and rear of said needles, and means for actuating said upper feed-dogs in timed relation with said lower feed-dog.

2. In a mechanism for simultaneously trimming both edges of a strip and reciprocally top feeding and finishing belt loops in a single operation, the combination with a sewing machine having a work supporting base and two spaced needles, two top feed-dogs placed one behind the other and being mounted for 4-motion feeding movements in front of said needles, means for resiliently and jointly downpressing said top feed-dogs, reciprocating shear blades mounted on a shaft positioned below said work supporting base, said blades being respectively positioned on opposite sides of the forward top feed-dog for cutting an automatically fed strip of fabric of predetermined width, a foot having two rigid side bars forming a fixed guideway centrally and lengthwise thereof, a folder for folding both side edges of said sheared strip of fabric underneath said strip and having a linear passage in its upper wall and a folding tongue positioned above said work supporting base, said reciprocating shear blades coating with stationary blades secured to opposite faces of a stationary blade carrier having a flat upper surface, said front top feed-dog being pivotally mounted on a pivot carried by said rear top feed-dog, and means for resiliently pressing said front top feed-dog against said surface independently of said joint resilient down-pressing, said surface being positioned in alignment with said folder tongue, the rear top feed-dog being mounted in said passage for feeding the folded fabric through said folder and along a portion of the length of said foot and directly to said needles, the width of said foot guideway being adapted for folded belt loops, a spring-pressed center presser-foot member vertically movable in said guideway and having needle holes, a lower feed-dog having feeding teeth only at its central portion and being positioned for movement inside said guideway for feeding folded belt loops pressed down by said center presser-foot member, said lower feed-dog

teeth being positioned at the front and rear of said needles, and means for actuating said upper feed-dogs in timed relation with said lower feed-dog.

3. In a mechanism for simultaneously trimming both edges of a strip and reciprocally top feeding and finishing belt loops in a single operation, the combination with a sewing machine having a work supporting base and two spaced needles and means for forming interlock stitching, two top feed-dogs placed one behind the other and being mounted for 4-motion feeding movements in front of said needles, means for resiliently and jointly downpressing said top feed-dogs, reciprocating shear blades mounted on a shaft positioned below said work supporting base, said blades being respectively positioned on opposite sides of the forward top feed-dog for cutting an automatically fed strip of fabric of predetermined width, a foot having two rigid side bars forming a fixed guideway centrally and lengthwise thereof, a folder for folding both side edges of said sheared strip of fabric underneath said strip into abutting relation, said folder having a linear passage in its upper wall and a folding tongue positioned above said work supporting base, said reciprocating shear blades coating with stationary blades secured to opposite faces of a stationary blade carrier having a flat upper surface, said front top feed-dog being pivotally mounted on a pivot carried by said rear top feed-dog, and means for resiliently pressing said front top feed-dog against said surface independently of said joint resilient downpressing, said surface being positioned in alignment with said folder tongue, the rear top feed-dog being mounted in said folder passage for feeding the folded fabric through said folder and along a portion of the length of said foot and directly to said needles, the width of said foot guideway being adapted for the passage of folded belt loops, a spring-pressed center member vertically movable in said presser-foot guideway and having needle holes, a lower feed-dog having feeding teeth only at its central lengthwise portion and being positioned for movement inside said guideway for feeding folded belt loops pressed down by said center presser-foot member, said lower feed-dog teeth being positioned at the front and rear of said needles, and means for actuating said upper feed-dogs in timed relation with said lower feed-dog.

JOSEPH GALKIN.
